UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,452, dated November 27, 1883.

Application filed September 26, 1883. Term of patent 3½ years.

To all whom it may concern:

Be it known that I, JOHN QUINCY REED, of the city, county, and State of New York, have invented and produced a new and original 5 Design for a Pattern of a Lady's Costume, (numbered 8,885;) and I do hereby declare that the engraved prints accompanying this specification convey to any one accustomed to using paper patterns a clear understanding of how 10 a garment made up by the pattern will appear.

The design shows a round walking-skirt with a polonaise, which latter has closely-fitted fronts, with a deep, pointed drapery having plaits in its back edges, and a closely-fitted back having plaits in its front edges, and

showing an under-folded triple box-plait at the lower end of the center seam, both draperies descending nearly to the bottom of the skirt. Coat-sleeves and a standing collar are added.

What I claim as my invention, and desire to secure by Letters Patent, is—

The design for a lady's costume, as shown in the engraved prints accompanying this specification.

JOHN QUINCY REED.
